CLAIM

The ornamental design for an insulating device as shown and described.

DESCRIPTION

FIG. 1 is a front view of an insulating device showing our new design;

FIG. 2 is a rear view thereof; and,

FIG. 3 is a top view thereof.

The zig-zag broken lines represent zipper teeth and form no part of the claimed design. The broken lines immediately adjacent to the shaded area define the bounds of the claimed design and form no part thereof. The broken lines depicting the remainder of the insulating device form no part of the claimed design.
